SEWING MACHINE

Harry Sebell, Marblehead, Mass., assignor of one-half to Richard Walsh McGann, Lexington, Mass., and one-half to Bell Products Corporation, Boston, Mass., a corporation of Massachusetts

Application June 16, 1945, Serial No. 599,873

5 Claims. (Cl. 112—186)

1

This invention relates to sewing machines and it has for its object to provide bobbin replenishing means constructed to extract an empty bobbin from the under thread mechanism of a two-thread sewing machine and to replace such empty bobbin with a filled bobbin.

A further object of the invention is to provide a bobbin replenishing mechanism which is provided with a magazine for holding filled bobbins and with bobbin extracting means together with devices by which the bobbin extracting element can be actuated to withdraw an empty bobbin from the bobbin case of the under thread mechanism and a filled bobbin can be introduced into the bobbin case from the magazine.

Other objects of the invention will be apparent from the following description of a selected embodiment of my invention.

In the drawings:

Fig. 1 is a side view of my improved bobbin-replenishing mechanism.

Figs. 2 and 3 are similar views showing the manner in which the empty bobbin is extracted from the bobbin case.

Fig. 4 is a top plan view of Fig. 1.

Fig. 5 is a fragmentary view showing the hook element and bobbin case of the under thread mechanism.

Fig. 6 is a fragmentary view showing one means of applying a retarding or braking action to the bobbin for the purpose of securing a proper tension on the under thread.

Fig. 7 is a section on the line 7—7 of Fig. 4.

In the drawings 1 indicates a portion of the frame of a two-thread sewing machine, 2 is the rotary hook element of the under thread mechanism and 3 indicates the bobbin case which is mounted in the rotary hook element and which is adapted to receive the usual bobbin 4 carrying the under thread. The bobbin case 3 is open on one side as usual and is provided with a usual axial stud 5 on which the bobbin 4 is mounted and by which it is centered. The hook element 2 is shown as carried by a driving shaft 8 that is mounted in the portion 9 of the sewing machine frame. The parts thus far described are such as are usually found in a two-thread sewing machine, and those skilled in the art will understand that when the sewing machine is in operation, the hook element 2 takes successive loops

of needle thread from the needle of the upper thread mechanism and casts each loop about the bobbin case thereby interlocking the needle or upper thread with the bobbin or lower thread.

5 In accordance with my invention, I have provided a bobbin replenishing mechanism which includes a bobbin extracting element for extracting an empty bobbin from the bobbin case 3 while the latter remains in the hook, and also 10 includes means for loading a filled bobbin into the bobbin case after the empty bobbin has been extracted and without removing the bobbin case from the hook.

Such bobbin replenishing mechanism includes 15 a magazine 10 which is provided with a chamber adapted to receive a series of filled bobbins 4 arranged in axial alignment, said magazine having a head 11 at its outer end from which extends an axial spindle 12 on which the filled bobbins 4 are threaded. Means are provided for 20 supporting this magazine 10 in axial alignment with the bobbin case 3 and shaft 8 and for this purpose said magazine is shown as provided with a supporting arm 13 which extends through apertured bosses 14 carried by a bracket 15 that is 25 secured to the portion 9 of the frame. The bracket 15 is shown as having an upturned end 16 which is clamped to the portion 9 of the frame by a clamping screw 17. The arm 13 is adjustable in the bosses 14 and is held in its adjusted position by set screws 18. The arm 13 is preferably flat sided as shown in Fig. 7 and the aperture through each boss 14 has a shape to fit the flat-sided arm so that the magazine will be firmly held in correct axial alignment with the bobbin case 3. The supporting bracket 15 is also shown as having an ear 20 at its outer end to which is 35 screw threaded a positioning screw 19 adapted to engage a shoulder on the arm 13 thereby to assist in correctly positioning the magazine with relation to the bobbin case. The screw 19 is shown as having a set nut 21 thereon.

The end of the magazine 10 which faces the bobbin case is open and in said open end is 45 mounted a bobbin extracting member 22 which is in the form of a sleeve that can move axially of the magazine 10. This sleeve 22 is formed at its outer end with a series of bobbin-gripping fingers 23 which are preferably slightly resilient. These 50 fingers 23 are arranged on a circle of a size to

enter the open end 40 of the bobbin case and to embrace the flange of the bobbin within the bobbin case. The bobbin extracting sleeve 22 is provided with an arm or handle by which it may be manipulated, said arm extending from the sleeve through a slot 26 with which the magazine is provided and terminating in a thumb piece 24 by which the sleeve can be moved lengthwise of the magazine. The bobbin extracting sleeve 22 is normally in the position shown in Fig. 1 and when a bobbin is to be extracted or removed from the bobbin case, the bobbin extracting sleeve is moved forwardly by the handle 24 from position in Fig. 1 to that shown in Fig. 2, and during such forward movement the fingers 23 enter the open side of the bobbin case and embrace the outer flange of the bobbin 4 with sufficient friction grip so that when the handle 24 is moved backwardly again as shown in Fig. 3, the said fingers will withdraw the bobbin from the bobbin case.

The magazine 10 is provided with a follower 27 adapted to engage the last bobbin of the row of bobbins within the magazine, said follower having an arm projecting therefrom through a slot 41 with which the bobbin case is provided which arm terminates in a finger piece 28 by which the follower 27 can be moved axially of the magazine 10. The follower is shown as provided with a pawl 29 adapted to engage ratchet teeth 31 formed on the edge of the slot 41, said pawl being held in engagement with the ratchet teeth by means of a suitable spring 30.

The follower 27 will be adjusted so as to maintain the end bobbin of the stack of bobbins substantially flush with the open end of the magazine as indicated in Figs. 1 and 2.

When the bobbin extracting sleeve 22 is moved backwardly to withdraw an empty bobbin from the bobbin case 3, such empty bobbin will engage the end filled bobbin in the magazine and as the bobbin extracting sleeve 22 is retracted into its rearward position, the empty bobbin will be stripped from the fingers 23 as shown in Fig. 3 and will fall by gravity into any suitable receptacle which may be provided for that purpose.

After the empty bobbin has been thus extracted from the bobbin case 3 through its open side, the operator presses forwardly on the finger piece 23 thereby advancing a stack of bobbins in the magazine and loading the end bobbin into the bobbin case through the same open side thereof.

Each of the filled bobbins 4 will preferably have a considerable length of thread trailing from it, and when the sewing machine is started after a filled bobbin has been loaded into the bobbin case, the first loop of upper thread which is cast about the bobbin case will pick up the trailing end of thread from the bobbin and will carry it into the proper position for forming the stitches thereby obviating any necessity for manipulating the under thread by hand to thread up the under thread mechanism.

In connection with my improvements, I have provided means for applying the necessary tension to the under thread by applying a braking or retarding action on the bobbin 4 within the bobbin case 3. While various ways of thus providing for such retarding action may be provided, I have herein shown a spring finger 33 which is associated with the stud 5 and which applies a retarding friction to the inside of the hub 32 of the bobbin. As herein shown, the hub 32 of the bobbin is concavo-convex and the spring finger 33 operates through a slot 34 with which the stud 5 is provided. The resiliency of the finger 33 pro-

vides sufficient friction between it and the inner face of the hub 32 to furnish a braking or retarding action on said bobbin that is sufficient to create the necessary tension on the under thread.

5 An advantage of making the hub 32 concavo-convex and making the finger 33 a curved finger as shown in Fig. 6 is that such finger not only provides the necessary braking action on the bobbin for the purpose of creating tension on the 10 under thread, but it also serves to hold the bobbin on the stud during the operation of the machine. The resiliency of the finger 33 permits the bobbin to be placed on the stud and as soon as the bobbin has been positioned within the bobbin case 3, the finger 33 springs outwardly into its frictional engagement with the inside of the hub 32 and thereby serves to retain the bobbin on the stud.

It will be understood, of course, that it is necessary to have the open side of the bobbin case free from any parts which would interfere with the loading of a bobbin into the case, and therefore, the usual bobbin retainer that in some machines is pivoted to the end of the stud 5 cannot be used.

I claim:

25 1. In a sewing machine the combination with a rotary hook and a bobbin case operatively associated therewith and having an open side, of bobbin-replenishing mechanism comprising a magazine to contain filled bobbins, means to extract an empty bobbin from the bobbin case through said open side while said case is still operatively associated with the hook, and means to load a filled bobbin from the magazine into the bobbin case through the same open side thereof.

2. In a sewing machine the combination with a rotary hook and a bobbin case associated therewith and having an open side, of bobbin-replenishing mechanism comprising a magazine open at one end and adapted to receive a plurality of bobbins arranged in axial alinement, means supporting the magazine with the bobbins therein axially alined with the open side of the bobbin case, means to extract an empty bobbin from the bobbin case through said open side while the bobbin case is still operatively associated with the hook, and other means to transfer a filled bobbin from the magazine to the bobbin case through the same open side thereof.

3. In a sewing machine the combination with a rotary hook and a bobbin case associated therewith, of a magazine open at one end and adapted to receive a plurality of bobbins arranged in axial alinement, means supporting the magazine with its open end directed toward the bobbin case and with the bobbins therein axially alined with said bobbin case, a bobbin-extracting sleeve carried by the magazine and movable axially thereof, said sleeve having resilient bobbin-engaging fingers on its forward end, means to move the sleeve forwardly on the bobbin case to bring said fingers into gripping engagement with the bobbin in the bobbin case and then to move the sleeve backwardly thereby to extract said bobbin from the bobbin case, and means to transfer the end bobbin in the magazine from the latter to the empty bobbin case.

4. In a sewing machine the combination with a rotary hook and a bobbin case located within the hook and provided with an open side, of bobbin-replenishing mechanism comprising means to extract an empty bobbin from the bobbin case through its open side while said bobbin case remains within the hook, and means to load a filled bobbin into the bobbin case through the

same open side while said case still remains within the hook.

5. In a sewing machine the combination with a rotary hook and a bobbin case located within said hook and provided with an open side, of a bobbin-replenishing mechanism comprising a magazine to contain filled bobbins, means to extract an empty bobbin from the bobbin case through its open side without removing the bobbin case from the rotary hook, and means to 10 load a filled bobbin from the magazine into the bobbin case through the same open side thereof while said case remains within the rotary hook.

HARRY SEBELL.
